COIN-COUNTING MACHINE

Earl W. Quirk, Watertown, and Arnold R. Buchholz, Dodge County, Wis., assignors to Brandt Automatic Cashier Company, Watertown, Wis., a corporation of Wisconsin

Application September 12, 1949, Serial No. 115,272

8 Claims. (Cl. 133—8)

1

The invention relates to coin counting machines adapted for automatically counting either an unlimited or predetermined number of coins of varying denominations, and if desired, depositing the same into a bag or a tube.

More particularly, the invention relates to that type of coin counting machine in which the coins are fed into a hopper having a revolving plate for its bottom by which the coins are fed by centrifugal force toward the periphery of the hopper having an opening at one side formed in part by an adjustable gate through which opening the coins pass to a discharge passage along which the coins are fed by a feed wheel past a counter operating star wheel prior to their discharge from the machine. In machines of the general type above described the feed wheel has either been a continuously rotated tiltable wheel or an intermittently rotated clutch controlled wheel as in U. S. Patent No. 2,378,828, dated June 19, 1945, to A. R. Buchholz et al., which also shows a predetermined count mechanism. One of the objects of the present invention is to provide novel mechanism for tilting a continuously rotatable feed wheel and control this mechanism through predetermined count mechanism preferably of the type shown in the said U. S. Patent No. 2,378,828.

A further object of the invention is to provide an improved tiltable feed wheel arrangement in which wear of the wheel may be readily compensated for.

A further object of the invention is to provide an improved form of starting control for coin counting machines of the general type above described whereby the count starting lever may be operated either by the usual hand lever or by a slight tilting of the coin discharge tube.

The invention further consists in the several features hereinafter set forth and more particularly defined by claims at the conclusion hereof.

In the drawings:

Fig. 1 is a top plan view of a coin counting machine embodying the invention;

Fig. 2 is a side elevation view of the machine;

Fig. 3 is a horizontal sectional view of the machine looking into it from the under side taken generally along the line 3—3 of Fig. 2 and with the motor removed;

Fig. 4 is a front end elevation view of the machine, parts being broken away and parts being shown in section showing the coin feed wheel in feeding position;

Fig. 5 is a view similar to Fig. 4 showing the coin feed wheel in its inoperative position;

2

Fig. 6 is a detailed vertical sectional view taken on the line 6—6 of Fig. 4;

Fig. 7 is a detailed vertical sectional view taken on the line 7—7 of Fig. 5, parts being broken away:

Fig. 8 is a side elevation view of parts shown in Fig. 7;

Fig. 9 is a detailed view of parts of the predetermined count mechanism.

10 Referring to the drawings, as in all machines of this general type, a counter 12 is provided which, as shown in Fig. 4, carries a bevel gear 13 meshing with a bevel gear 14 on an upright shaft 15 carrying a coin operated star wheel 16, the coins being fed past said wheel 16 by a feed wheel 17 as they are delivered to the wheel 17 through an adjustable opening at one side of a hopper 18 whose bottom 19 is in the form of a disk or round plate carried by a vertically disposed shaft 20 suitably journaled in the top plate 21 and carrying a spiral gear 22 meshing with a spiral gear 23 on the main drive shaft 24, see Figs. 3, 4, and 5.

25 As in the Buchholz et al. patent, the adjustable gate which determines the size of the discharge opening from the hopper 18 is vertically adjustable by the turning of a screw shaft carrying a handle 25. Also in accordance with known practice, a gauge plate 26 is slidably mounted relative to the start wheel 16 to adjust the width of the passage 27 for the particular coins being counted and is locked in position by a hand clamp C.

30 Beyond the wheel 16 the discharge passage 27 is inclined as in Fig. 6 at 28 to discharge the counted coins into a tube section 29 which has a coin deflector 30 projecting above the outlet end of the passage 27. A discharge tube 31 has its upper end removably secured in the lower end of the section 29 by a spring pressed detent 32 engageable with an opening 33 in said tube 31 which is loosely mounted in the section 29 so that it may be tilted upwardly about the pin or detent 32 as a fulcrum so as to engage and press 35 upwardly on a plunger 34 normally held against movement by a spring 35 and adapted when moved to engage one arm of a rocker lever 36 pivoted at 37 and having its other arm 38 operatively engageable with a link 39 forming part 40 of a count starting control hereinafter described.

45 Referring to Fig. 2, an electric motor 40 has a pulley 41 mounted on its drive shaft and connected by a belt 42 with a pulley 43 on the main drive shaft 24.

50 Referring to Figs. 2, 4, and 5, the feed wheel 17, which has a rubber coin contacting face 17a, is

mounted on a shaft 44 carrying a pulley 45 connected by a belt 46 with a pulley 47 on the drive shaft 24. The shaft 44 is mounted in a rear bearing 48 and a front bearing 49, both of which are carried by a tiltable support 50 mounted to turn on a pivot shaft 51. The rear bearing 48 is pivotally supported in the support 50 by trunnions 52. The front bearing 49, as shown in Fig. 6, is vertically slidably mounted in a box 53 formed as part of the support 50 and has a threaded bore 54 engaged by a manually adjustable screw shaft 55 journaled in the top wall of the box 53 so that turning of the shaft 55 will move the bearing 49 relative to said support so that it may be tipped about the rear bearing to various angular positions relative to the support 50 to compensate for wear of the face 17a. When once adjusted the actual tilting of the shaft 44 to bring the wheel 17 into and out of feeding engagement with the coins is done by tilting the support 50 about its pivot 51. The shaft 55 is turned by a thumb wheel 56 which is of the locking type, that is, it is lengthwise movable on the shaft 55 and yieldingly urged toward the box 53 by a spring (not shown) so that its diametrically disposed projections 57 may engage in similarly disposed recesses 58 in the top of the box.

The support 50 is moved to a feed wheel release position by the action of a belt tensioner acting on the belt 46. This tensioner (see Figs. 2 and 4) includes a pulley 59 engageable with the belt and carried by an arm 60 mounted to swing on a fixed stud 61 and urged to tensioned position by a spiral spring 62.

The support 50 is moved to feed wheel operative position by a plunger means shown in Figs. 4 to 8 and comprising a pair of plunger members 63 and 64 working in a guide tube 65 and operatively connected together by a coiled spring 66 so that the plunger member 63 operatively connected at 67 with the support 50 may yield relative to the plunger member 64 in case a coin should become jammed between the wheel and the discharge chute. The spring 66 also acts to exert a yielding downward pressure on the wheel 17. A plunger operating lever 68 is pivotally mounted intermediate its ends at 69 on a fixed part of the machine and at one end 70 engages the outer end of the plunger member 64 and at its other end 71 engages a stop 72 in its release position. The lever 68 is pivotally moved to raise the plunger means by a one revolution cam 73 which is slidably keyed on the shaft 24 by a diametrically disposed pin 74 mounted in said shaft and working in diametrically disposed slots 75 in the hub of the cam. A spring 76 normally urges the cam 73 to a release position against a stop collar 77 on the shaft 24. When permitted to do so, a wedge member 78 pivoted at 79 and urged toward the hub of the cam by a spring 80 acts to move the cam 73 from the position shown in Fig. 5 to the position shown in Fig. 8 at which time the turning of the shaft 24 acts through said cam on the lever 69 to move the plunger means from the position shown in Fig. 5 to the position shown in Fig. 4 at which time the support 50 has been tilted and the feed wheel 17 is in coin feeding position. The wheel is retained in this position by locking the plunger member 64 by means of a latch 81 pivotally supported at 82, see Fig. 3, and working in a slot 83 in the tube 65 and engageable with an annular groove 84 in the member 64.

The wedge member 78 is moved to inopera-

tive position against the action of its spring 80 after the cam 73 has moved the plunger 64 inwardly by providing a projection 85 on the member 78 extending into the path of movement of the lever 68, so that when the cam 73 has moved the lever 68 to the position shown in Fig. 4, the other end of said lever strikes the projection 85 and swings the wedge 78 outwardly to a release position.

The operation of the cam 73 and the latch 81 are controlled by the mechanism associated with the counter which is adapted to move the cam 73 to a position in which the wedge 78 is effective to move it to a position for engaging the lever 68 at the start of the count to bring the feed wheel 17 to coin feeding position and to move the latch 81 to a release position at the end of the count of a predetermined number of coins so that the feed wheel 17 may be swung upwardly out of coin feeding position. The predetermined count mechanism that we have chosen to illustrate in connection with the present invention is substantially identical with that shown in the Buchholz et al. Patent No. 2,378,828, and Fig. 3 of the present application shows the parts of this mechanism in the same position as Fig. 10 of that patent and in what has been described therein as the pre-set position while Fig. 9 shows parts of the structure shown in Fig. 8 of said patent. It is believed that this showing is sufficient for the understanding of the present invention and avoids a duplication of Figs. 9 and 11 of said patent.

As in the aforementioned patent, the number of coins to be counted is determined by the setting of a lever L of known form having a part adapted to engage a pin 86 on a counter operated ratchet wheel 87, said pin extending through an arcuate slot 88 in a base plate 89. As in the patent, the ratchet wheel 87 is turned in one direction by a spring 90 and in the opposite direction by a cam or tooth member 91 on the inner end of the shaft 15 that carries the coin operated star wheel 16. The wheel 87 is prevented from being turned backwardly by the spring 90 by a holding pawl 92 pivoted at 93. The tooth spacing of the wheel 87 is such that for five coins fed through the discharge passage on each revolution of the star wheel, the ratchet wheel 87 is advanced one tooth. For a continuous count, the lever L is moved so that the spring 90 may turn the wheel 87 to a position in which its toothed section is out of mesh with the cam member 91. For predetermined counts the lever L acts on the pin 86 to set the wheel 87 to a predetermined position, and as shown in Fig. 3, the wheel, set for the counting of ten coins, has been moved to a pre-set position as the seventh and eighth coins are counted as described in said patent. Thereafter, the cam 91 is turned clockwise as viewed in Fig. 3 as the ninth and tenth coins are fed past it. While the tenth coin is passing, the star wheel, the cam 91 moves to operate a three arm lever 94 pivotally mounted at the outer end of a lever 95 corresponding to lever 59 of the patent, said cam acting on a pin 96 on one arm of the lever to swing the lever 95 clockwise, thereby causing a pin 97 on a second arm of said lever working in a slot in the pawl 92 to release said holding pawl and also causing a pin 98 on the third arm of the lever to push toward the right against a plunger release link 99 which is pivotally connected by a pin 100 to the plunger locking latch 81, moving said link, so as to swing said latch to a release position so the plunger means previously de-

scribed is free to return to its initial position shown in Fig. 5 under the action of the belt tensioner spring 62, and the wheel 17 is moved to its inoperative or non-feeding position.

For starting the operation of the counting mechanism a re-set member 101 similar to the member 99 of the patent is pivoted on a pin 102 mounted on the base plate and has a hand lever extension 103 to which the link 39 previously referred to is pivotally connected at 104, said member 101 being normally urged to an inoperative position by a spring 105. Member 101, as shown in Fig. 9, has a dog 106 pivotally mounted thereon at 107 which is adapted to engage a pin 108 on a pivoted latch member 109, corresponding to the member 87 of said patent, so as to swing said latch member out of holding engagement with the lever 95 so that the spring 110 connected to said lever may swing it and the lever 94 back to their initial position in which the cam 91 is again effective to turn the ratchet wheel 87 and thereafter move the lever 94 as previously described, it being noted that in the pre-set position of the mechanism a pin 111 on the ratchet wheel 87 has engaged the lever 95 and moved it clockwise to a position in which its shoulder 112 may be engaged by the end 113 of the latch 109 at which time the three arm lever 94, as shown in Fig. 3, is in a position for actuation by the cam 91. In addition to acting as a re-set member for the predetermined count mechanism said member 101 also carries parts for initially advancing the cam 73 to a position in which the wedge 78 may be effective to complete the movement of said cam to a driving position relative to the lever 68. The parts which thus function to move the cam include a finger 114 which is pivotally mounted on a pin 115 carried by the outer end 116 of the re-set member 101 so as to swing therewith and which also has swinging movement relative thereto determined by a pin 117 mounted on the finger and extending through an arcuate slot 118 in the end 116 into a cam slot 119 in a plate 120 fixed to the base plate 89, said finger being normally urged to swing clockwise as viewed in Fig. 3 by a spring 121. With this arrangement as the end 116 of the re-set member 101 is swung toward the right to release the latch 109 as previously described, the finger 114 also swings to the right until its end 122 engages an annular curved rib 123 on the hub of the cam 73, and as it continues to swing in this direction, it pushes said cam 73 toward the right to the position where the wedge 78 may engage between the collar 77 and the cam so as to shift the cam into the position shown in Fig. 8, so that said cam 73 may operate the lever 68 to move the plunger means previously described so as to tilt the support 50 to a position in which the feed wheel 17 is operative to feed coins past the star wheel 16. As the finger 114 completes the initial feeding movement of the cam 73, its pin 117 engaging the cam slot 119 swings the end 122 of said finger out of contact with the rib 123, and on the return stroke of the re-set member 101 said finger is free to swing by the rib 123. Thus the cam 73 with its associated parts forms a one revolution actuating means for moving the feed wheel support to a position in which the feed wheel is operative to feed coins.

To briefly sum up the operation of the machine. With the motor 49 running so that the disk 19 is revolving and the feed wheel 17 is also rotating in the position shown in Fig. 5, no coins can pass the star wheel 16. If now either the handle 103 is swung toward the left as viewed in

Fig. 3 or the coin receiving tube 31 is tilted toward the left as viewed in Fig. 6 so as to move plunger 34 to swing lever 36 so as to shift link 39 to the left, the re-set member 101 is moved to reset the predetermined count means, and the cam 73 is moved by the finger 114 to a position where the wedge 78 is effective to move it into and hold it in engagement with the lever 68 which is then operated from the drive shaft 24 through said cam to move the plungers 63 and 64 from the position shown in Fig. 5 to the position shown in Fig. 4, it being noted that as plunger 64 is locked by the latch 81, the lever 68 acting on the projection 85 moves the wedge 78 to inoperative position so that the cam 73 after a single rotation is moved back to its initial position by the spring 76. The parts are now in position for the feed wheel 17 to feed the coins past the star wheel 16 which it proceeds to do until said star wheel has turned the cam member 91 through two or more revolutions to advance the ratchet wheel 87 two or more teeth depending upon the setting of the lever 85 at which time the pin 111 acts on the lever 95 swinging it down so that the cam 91 acting through lever 94 on link 99 may release latch 81 so as to release the pressure of the plunger means on the support 50 to permit the support with said wheel 17 to move to the inoperative position shown in Fig. 5 under the action of the belt tensioner.

It will be noted from the foregoing that we have provided means driven by the machine for moving the feed wheel to operative position which means includes a shiftable cam driven by the drive shaft 24 and controlled by the count starting control or re-set member 101 for moving the lever 68 operating on a shiftable link means comprising the plungers 63 and 64 and the spring 66 to tilt the tilttable support 50 to a position in which the feed wheel 17 is in coin feeding position and that the predetermined count mechanism including the release link 99 controlled by the coin operated cam 91 acts through the latch 31 to control the movement of the support 50 to a position in which the feed wheel is inoperative. Also that in case the feed wheel face 17a should wear, the shaft 44 may be shifted relative to the support 50 to compensate for this wear. Finally in operations where the predetermined number of coins are fed into tubular containers, it is not necessary for the operator to use one of his hands to operate the lever 103 to start the counting operation, but this may be effected by tilting the coin tube 31 by the same hand that is holding the container to be filled at the lower end of said tube.

We desire it to be understood that this invention is not to be limited to any particular form or arrangement of parts except in so far as such limitations are included in the appended claims.

What we claim as our invention is:

1. In a coin counting machine having a counting device, a continuously rotated feed wheel for feeding coins past the counting device to actuate the same, said feed wheel being mounted on a tilttable support for movement to an operative and an inoperative position, the combination of a cam driven by said machine, a lever engageable by the cam, and a yieldable link connection between said lever and said support for tilting said support to a feed wheel operative position, a latch for locking said linkage in feed wheel operative position, predetermined count mechanism for releasing said latch after a predetermined number of coins have been fed past said

counting device, and a starting control for said mechanism and for said cam.

2. In a coin-counting machine having a counting device, a motor, a feed wheel continuously rotated by said motor for feeding coins past said counting device to actuate the same, a movable mounting for said feed wheel to permit positioning said wheel in a coin feeding position and an inoperative position, and predetermined count mechanism, the combination of mechanism controlling the movement of said mounting comprising a one revolution actuating means driven by said motor and operatively connected to said mounting and rendered operative on the starting of the operation of said predetermined count mechanism for moving said mounting to position said feed wheel in coin feeding position, means for holding said mounting in its coin feeding position, means for moving said mounting to position said wheel in an inoperative position, and means controlled by said predetermined count mechanism for releasing said holding means so that said last named means is operative to move said mounting to position said wheel in an inoperative position when a predetermined number of coins have been fed past said counting device.

3. A coin counting machine as defined in claim 2 in which said one revolution actuating means is rendered operative by the starting control of said predetermined count mechanism.

4. In a coin counting machine having a counting device, a motor, a feed wheel continuously rotated by said motor for feeding coins past said counting device to actuate the same, a movable mounting for said feed wheel to permit positioning said wheel in a coin feeding position and in an inoperative position, and predetermined count mechanism, the combination of mechanism controlling the movement of said mounting comprising a one revolution cam means driven by said motor and operatively connected to said mounting and rendered operative on the starting of the operation of said predetermined count mechanism for moving said mounting to position said feed wheel in coin feeding position, means for holding said mounting in its feed wheel coin feeding position, means acting automatically when a predetermined number of coins have been fed past said counting device to release said holding means, and means for moving said mounting to position said wheel in an inoperative position on the release of said holding means.

5. In a coin counting machine having a counting device, a motor, a feed wheel continuously rotated by said motor for feeding coins past said counting device to actuate the same, a movable mounting for said feed wheel to permit positioning said wheel in a coin feeding position and in an inoperative position, and predetermined count mechanism having a starting control, the combination of a shiftable cam having an operative

and inoperative position and driven by said motor, means operated by said cam to move said mounting to feed wheel coin feeding position, means for shifting said cam to an inoperative position relative to said last named means after a single revolution of said cam, means for shifting said cam to its operative position including a member operated by the starting control of the predetermined count mechanism, means for holding said mounting in its feed wheel coin feeding position, means controlled by said predetermined count mechanism for releasing said holding means after a predetermined number of coins have been fed past said counting device, and means for moving said mounting to position said wheel in an inoperative position on the release of said holding means.

6. A coin-counting machine as defined in claim 5 in which the means for shifting the cam to its operative position also includes a spring operated wedge rendered operative by the initial movement of the cam by the aforementioned member operated by said starting control.

7. A coin-counting machine as defined in claim 5 in which the cam operated means for moving said mounting includes a lever and a yieldable plunger engaged by said lever and in which the means for shifting the cam to its operative position also includes a spring operated wedge which is released by said lever after a single revolution of the cam.

8. In a coin-counting machine having a counting device, a motor, a feed wheel continuously rotated by said motor for feeding coins past the counting device to actuate the same, said feed wheel being movably mounted for movement to an operative position and an inoperative position, and predetermined count mechanism, the combination of means driven by said motor for moving said feed wheel to its operative position, means for holding said feed wheel in its operative position, means controlled by said predetermined count mechanism for releasing said holding means, and means for moving said feed wheel to its inoperative position.

EARL W. QUIRK.

ARNOLD R. BUCHHOLZ.
